UNITED STATES PATENT OFFICE.

JAMES B. SMITH, OF FALLS CITY, NEBRASKA.

WRENCH.

SPECIFICATION forming part of Letters Patent No. 473,026, dated April 19, 1892.

Application filed July 24, 1891. Serial No. 400,543. (No model.)

To all whom it may concern:

Be it known that I, JAMES B. SMITH, a citizen of the United States, residing at Falls City, in the county of Richardson and State of Nebraska, have invented certain new and useful Improvements in Wrenches; and I do declare the following to be a full, clear, and exact description of the invention, such as will enable others skilled in the art to which it appertains to make and use the same.

My invention has relation to improvements in wheel-nut wrenches; and it consists in the construction, novel combination, and adaptation of the parts hereinafter described and claimed.

In the accompanying drawings, Figure 1 is a side elevation of my improved wrench in an operative position upon a wheel. Fig. 2 is a perspective view of the wrench removed. Fig. 3 is a detail perspective view of a modified construction of spoke-engaging hook and lever-arm. Fig. 4 is a similar view of another modified construction of spoke-engaging hook and lever-arm, and Fig. 5 is a perspective view of modified lever-arms.

Referring by letter to said drawings, A indicates the lever-arms of my improved wrench, which have their inner connected ends enlarged, so as to insure a firm engagement of the nut or burr to be removed. These arms A may be constructed entirely of wood or metal; but I prefer in practice to form the inner or engaging ends of iron or other suitable metal and the outer portion of hickory or other suitable wood. Pivots connected to the sides of both of the lever-arms adjacent the inner ends thereof, or pivotally connected to one arm and fixedly connected to the other, are connecting-plates or link-straps B, which are preferably provided with auxiliary bolt-holes, as illustrated, whereby the distance between the adjacent ends of the lever-arms may be increased or diminished, so as to enable the said arms to receive nuts or burrs of various sizes between them.

Flexibly connected, by leather straps *a* or the like, to the lever-arms A, adjacent the outer ends thereof, are the spoke-engaging hooks C, which extend laterally from the said arms and are preferably constructed of wood or other suitable material not calculated to scratch or otherwise mar the spoke when the

wrench is in operation. By this construction it will be readily perceived that when the lever-arms are mounted upon the burr or nut 55 and the hooks C connected to the spokes of the wheel the nut may be readily removed from the spindle by turning the wheel backwardly, after which the wheel and nut may be removed together.

In Fig. 3 of the drawings a modification of the lever-arms and spoke-engaging hooks is disclosed, which construction is designed to render the lever-arms capable of engaging very small nuts. Referring by letter to the 65 said figure, A' indicates a portion of one of the lever-arms, which are respectively provided with a longitudinal slot *b* adjacent their outer ends. These slots *b* of the lever-arms are designed to receive the reduced and 70 threaded shanks *c* of the spoke-engaging hooks C', which are adjustably connected to the lever-arms by the small nut *d*. By this construction when it is desirable to remove a very small nut—such as employed upon 75 sulkiies and other light vehicles—it is simply necessary to loosen the nuts upon the shanks of the spoke-engaging hooks, after which the wrench is connected to the nut and wheel, as before described. The spoke-engaging hooks 80 are then adjusted toward the inner ends of the lever-arms and are fixed in such position by the nuts *d*. Thus it will be readily perceived that the outer ends of the lever-arms will be held in, adjacent to the wheel, and 85 their inner engaging ends will be brought close together, enabling them to firmly engage a small-sized nut.

In Fig. 4 of the drawings I have disclosed another modification of the lever-arms and 90 spoke-engaging hooks which is designed for the same purpose as the construction illustrated in Fig. 3—viz., to enable the lever-arms to engage and remove small-sized burrs and nuts. In the said figure, A'' indicates the outer 95 portion of one of the lever-arms, which are provided with transverse apertures designed to receive the shanks of the spoke-engaging hooks C'', which in this construction are preferably composed of round bar metal and preferably have their engaging ends covered, so as to avoid scratching the spokes. The inner end of the shank of the hooks C'' is threaded, as illustrated, to receive a nut *d'*, and inter-

posed between said nut and the lever-arm is a coiled spring D, which surrounds the hook-shank and is preferably of a resiliency adapted to afford a slight give to the hook, which is highly desirable in some cases.

In applying a wrench embodying this latter construction the wrench is mounted as before described, when, if it is desirable to engage a small nut, the nut d' is turned so as to draw the outer ends of the lever-arms toward the wheel, which diminishes the distance between the inner engaging ends of said arms and enables said ends to firmly grasp the nut.

15. In Fig. 5 of the drawings I have disclosed a modification of the lever-arms and the manner of connecting the same. Referring by letter to said figure, A³ A⁴ indicate the lever-arms, the arm A⁴ of which is provided at its 20 inner end with a rigid angular jaw, to the sides of which two straps B' are pivotally connected, which straps are provided at their opposite end with eyes to receive a transverse connecting bolt, which takes through the straps and the end of the arm A³, which rests between said straps. The arm A³ is provided with a movable angular jaw E, to which is connected one end of a threaded rod F, the opposite end of which takes loosely through 25 the lug G, between the branches of which a screw-threaded disk M is mounted on the rod F, whereby the jaw E is adjusted to and from the end of the arm.

Having described my invention, what I 35 claim, and desire to secure by Letters Patent, is—

1. In a wheel-wrench, the combination, with two lever-arms having their adjacent ends adapted to engage a nut from opposite sides, 40 and straps or plates flexibly connecting the inner ends of the same, of the spoke-engaging hooks connected to said lever-arms and extending laterally therefrom, substantially as specified.

45. 2. In a wheel-wrench, the combination, with two lever-arms having their adjacent ends adapted to engage a nut from opposite sides, of connecting straps or plates pivotally connected to said arms adjacent the inner ends thereof, and spoke-engaging hooks connected to the lever-arms and extending laterally therefrom, substantially as and for the purpose specified.

50. 3. In a wheel-wrench, the combination, with

two lever-arms having their adjacent ends 55 adapted to engage a nut from opposite sides, of the straps or plates flexibly connecting the inner ends of said lever-arms and having the auxiliary bolt-holes, and suitable devices for connecting the free or outer ends of the lever-arms to the spokes of a vehicle-wheel, substantially as specified.

4. In a wheel-wrench, the combination, with two lever-arms having their adjacent ends adapted to engage a nut from opposite sides, 60 and connecting straps or plates pivotally connected to said arms adjacent the inner ends thereof, of the spoke-engaging hooks, and flexible straps connecting said hooks to the lever-arms, substantially as specified. 70

5. In a wheel-wrench, the combination, with two levers flexibly connected at their inner ends and having longitudinal slots adjacent their outer ends, of spoke-engaging hooks having threaded shanks adapted to take 75 through the slots of the lever-arms, and nuts mounted on the threaded shanks of the said hooks, substantially as specified.

6. In a wheel-wrench, the combination, with two levers having their adjacent ends adapted to engage a nut from opposite sides, flexibly connected at their inner ends and having transverse apertures adjacent their outer ends, of spoke-engaging hooks having threaded shanks adapted to take through the apertures of the lever-arms, the nuts upon the ends of said hooks, and coiled springs interposed between the nuts and lever-arms and surrounding the hook-shanks, substantially as specified. 80

7. In a wheel-wrench, the combination, with a lever-arm having a rigid jaw at its inner end and two straps pivotally connected to the side of said jaw, of a lever-arm having its inner end pivotally connected between the said straps, a sliding jaw mounted on the latter arm, a threaded rod connected to the sliding jaw and taking through a lug on the lever-arm, and a threaded disk mounted on the threaded rod between the branches of the 95 said lug, substantially as specified. 100

In testimony whereof I affix my signature in presence of two witnesses.

JAMES B. SMITH.
